Primary Examiner—Bernard Ansher*Assistant Examiner*—Philip Hyder*Attorney, Agent, or Firm*—Baker & McKenzie[57] **CLAIM**

The ornamental design for handle for a kitchen tool, as shown.

DESCRIPTION

FIG. 1 is a top plan view of a handle for a kitchen tool, showing my new design;

FIG. 2 is a front elevational view thereof, the rear view being a mirror image; and,

FIG. 3 is a left side elevational view thereof.

The broken line showing of the cheese slicer is for illustrous purposes only and forms no part of the claimed design.

The right side of the handle is plane and unornamented.
